Dated ^{Oct 20 1931}

UNITED STATES PATENT OFFICE

FREDERICK GUY ROBINSON, OF KINGSTON-UPON-HULL, ENGLAND

MOUNTING OF TAGS FOR CAN-LIKE CONTAINERS

Application filed February 4, 1931, Serial No. 513,400, and in Great Britain February 15, 1930.

This invention relates to paint and like cans of the kind provided with means for positively engaging a device, indicating the colour, quality or other particulars of the 5 contents of the can, to prevent its lateral movement around or along the top beaded edge or rim of the can body, the upper or clip portion of the indicating device for this purpose being formed with a through hole 10 adapted to be engaged by a projection or tongue on the lid when the latter is placed in position.

According to the present invention, a 15 through hole is formed in the lid instead of in the upper or clip portion of the indicating device, and the latter is provided or formed with a tongue or projection adapted to be passed through said hole so as to prevent lateral movement of the indicating device 20 around or along the top beaded edge or rim of the can. The through hole may be formed in the lateral flange of the lid or through a lip extending therefrom, whilst the tongue or projection of the upper or clip portion 25 of the indicating device, after being passed through the hole in the flange or lip of the lid from the underside thereof, may be bent downwardly into the well or dished portion of the lid so as to lie against the inner face 30 of the upstanding wall or flange of said lid.

In order that the invention may be clearly understood and readily carried into effect, the same will now be more fully described with reference to and by the aid of the 35 accompanying drawings; wherein:—

Figure 1 is a side elevation of a circular paint can be fitted with an indicating device according to the invention.

Figure 2 is a part section on line A—A of 40 Figure 1 drawn to an enlarged scale for the sake of clearness.

Figure 3 is a plan of Figure 2.

Figures 4 and 5 are similar views to Figures 2 and 3 but show a modified form of 45 clip.

Figures 6 and 7 are also similar views to Figures 2 and 3 but show another modified form of clip.

Referring to the drawings, 1 is a lever-lid 50 can, 2 is the indicating device provided at

the top with a clip portion 3 adapted to engage the beaded edge 4 of the can body 1. The lid 5 is provided with a lip 7 adapted to bear upon the clip portion 3 of the indicating device 2 and prevent the latter being forced upwardly. 55

In order to prevent lateral or vertical movement of the indicating device 2 the clip portion 3 thereof is extended to form a tongue 3^x which is passed through a slit 6 in the lip 7 of the lid flange 8. As shown at Figures 2 and 3 the lid flange 8 is downwardly cranked or offset at the place where the slit 6 is formed and the tongue 3^x after passing therethrough is bent downwardly so as to lie 60 against the wall of the lid recess. In the modified form shown at Figures 4 and 5 the clip portion 3 is shaped to fit the beaded edge 4 and the extended tongue portion is passed upwardly through a slit 6 and then secured 65 in position by bending outwardly on the lip 7 of the lid flange. In the form shown at Figures 6 and 7 even greater security is afforded by forming two slits 6 in the lip 7 and the flange respectively, and passing the 70 tongue portion of the clip upwardly through the outer slit and downwardly through the inner. If desired, the tongue portion may be passed downwardly through the outer slit and upwardly through the inner slit and may be 75 finished by bending into the lid recess as in Figure 2. 80

The tongue or projection on the indicating device, when passed through the hole in the lid flange from the underside, prevents the 85 indicating device as a whole being displaced vertically, whilst in order to prevent removal of the indicating device its tongue or projection may be provided or formed with a cut and raised portion or lip which is adapted 90 to engage the side of the hole in the lid flange through which said tongue or projection is passed.

The lower part of the indicating device 2 tends to keep closer to the side of the tin and is thereby less liable to damage if the upper part presses against the bead of the tin rather than against the body of the tin, and in this connection the upper edge of the indicating device 2 at either side of the clip portion may 95

be adapted to press against the outer portion or against the underside of said bead.

I claim:—

- 5 1. The combination with a can-like container having its lid provided with an apertured lip, of a device for identifying a characteristic of the contents of the container having a tongue which extends through the aperture in the lid and is bent laterally above the lid.
- 10 2. The combination with a can-like container having its lid formed with a central depressed portion and provided with an apertured lip projecting from the marginal wall of said depressed portion, of a device for identifying a characteristic of the contents of the container having a tongue which extends through the apertured lip and has its end bent downward into the depressed portion of the lid.
- 15 3. The combination with a can-like container having two, radially spaced, apertures formed in a lip on its lid, of a device for identifying a characteristic of the contents of the container having a tongue which is passed through both said apertures.
- 20 4. The combination with a can-like container having an aperture formed in a lip on its lid, of a device for identifying a characteristic of the contents of the container having a tongue which extends upward through said aperture in the lid and is bent radially outward of said lip above the lid.

FREDERICK GUY ROBINSON.
